TRANSFORMER CUT-OUT FOR ALTERNATING-CURRENT CIRCUITS.

1,036,696.

Specification of Letters Patent. Patented Aug. 27, 1912.

Application filed July 15, 1909. Serial No. 507,750.

To all whom it may concern:

Be it known that I, JOHN SEDGWICK PECK, a citizen of the United States, and a resident of Trafford Park, Manchester, England, have invented a new and useful Improvement in Transformer Cut-Outs for Alternating-Current Circuits, of which the following is a specification.

My invention relates to alternating current electric distribution systems and particularly to systems in which main and auxiliary transformers are employed.

It has heretofore been proposed to provide an automatic switching device to be operated through a relay by variations in the current supplied to, or delivered by, the transformers, for short circuiting the auxiliary transformer primary and secondary windings, when a series system is employed, or for opening and closing the primary and secondary windings of the main transformer when a parallel system is utilized.

One object of the present invention is to provide improved devices in connection with the relay switch which governs the operation of the automatic switch, another object of the invention being to provide an improved device whereby the blowing of a fuse in the auxiliary transformer circuit when the main transformer is not in use shall cause the automatic switch to close and thereby transfer the load to the main transformer in order to avoid interruption in the supply of energy.

In systems where main and auxiliary transformers are so arranged that their secondary windings are connected in parallel to supply energy to a three-wire circuit, it has hitherto been considered necessary to install two switches in the secondary circuit, one switch being in the neutral wire which is connected to the middle point of the main transformer secondary winding, and the other being in the circuit of one outer conductor which is connected to one end of the said secondary winding, or a switch is employed in each outer conductor.

A further object of the present invention is to provide an improved arrangement for opening and closing the connections of the main transformer to the circuit, in a system of the above mentioned character, in which only a single switch is required.

In the accompanying drawings, Figures 1,

2, 3 and 4 are diagrammatic views of distribution systems embodying my invention.

Referring now to Fig. 1, which illustrates a distribution system having main and auxiliary transformers connected in series with one another, a main transformer being indicated at 1 as having a primary winding 3 and a secondary winding 4, and an auxiliary transformer being indicated at 2 as having a primary winding 5 and a secondary winding 6. The primary windings 3 and 5 are connected in series with each other between the conductors 7-8 of the supply circuit, and the secondary windings 4 and 6 are similarly connected. The primary winding 5 of the auxiliary transformer 2 is arranged to be short circuited by means of a switch 15 when the load on the system becomes considerable, and the secondary winding 6 of the transformer 2 is arranged to be similarly short circuited by means of a switch 14 comprising fixed contact terminals 12 and 13 which are connected, respectively, to the junction 11 of the windings 4 and 6 and to a conductor 10 of the distributing circuit 9-10. The movable bridge pieces 45 and 16 of the respective switches 14 and 15 are arranged to be operated by means of an electro-magnetically actuated member 17 which is provided with a closing coil 18 and an opening coil 19. One terminal of the closing coil 18 is connected to the contact terminal 13 of the switch 14 and one terminal of the opening coil 19 is connected to one of the stationary contact terminals 20 of a switch 21, the other stationary contact terminal 22 of which is connected through indicating lamps 23 to the conductor 9 of the distributing circuit. The other terminals of the opening coil 19 and the closing coil 18 are connected, respectively, to the contact terminals 24 and 25 of a relay switch 26 having a contact arm 27 which is electrically connected to the conductor 9 and is arranged to be moved against the action of a spring 28 by means of an electro-magnet 29 in order to effect engagement with the contact terminal 24. The coil of the electro-magnet 29 may be supplied with current from the secondary winding 30 of a series transformer 31, the primary winding 32 of which is connected in the conductor 8 of the supply circuit. A contact terminal 33 of the switch 15 is connected to an intermediate point in

the winding 32 of the series transformer 31, so that, when the switch 15 is closed, a portion of the turns of the winding 32 are short circuited to reduce the voltage impressed upon the coil of the electro-magnet 29 of the relay switch 26.

The movable contact member 34 of the switch 21 is pivoted at 35 and is normally held in engagement with the contact terminal 20, against the action of a weight 36, by means of a bell crank lever 37, one arm 38 of which engages a projection 39 on said contact member and the other arm 40 of which is connected to a fuse 41 which is included in circuit with the conductor 10 of the distributing circuit. The member 17 is provided with a projection 42 to be engaged by contact member 34 to move the switches 14 and 15 into their closed positions.

The operation of the apparatus is as follows: When the load upon the system is light, the various switches occupy the positions illustrated in Fig. 1 and the main and auxiliary transformers are connected in series with each other across the supply and distribution circuits. If, however, the load increases to a predetermined value, the current traversing the series transformer 31 becomes sufficient to so energize the electro-magnet 29 that it will move the member 27 of the relay switch 26 into engagement with the contact terminal 24. A circuit is thereby completed through the closing coil 18 of the switches 14 and 15 whereby said switches are closed and the auxiliary transformer windings 5 and 6 short circuited. Under such conditions, the primary winding 32 of the series transformer 31 may be traversed by a large current which corresponds to the maximum load on the system. A correspondingly large current would be supplied to the coil of the electro-magnet 29 if it were not for the fact that the switch 15 short circuits a portion of the winding 32 of the transformer 31, and thereby reduces the maximum ampere turns in the electro-magnet 29 to such degree that danger of injury to the coil by over-heating is greatly reduced. If the load on the supply circuit be reduced below the predetermined value at which the electro-magnet 29 is adjusted to operate, the member 27 of the relay switch 26 will be moved by the spring 28 into engagement with the contact terminal 25 and a circuit will thereby be completed through the opening coil 19 to open the switches 14 and 15. If, at any time during the operation under light load conditions, the current traversing the winding 6 of the auxiliary transformer 2 increases to such proportions as to blow the fuse 41, the bell crank lever 37 will release contact member 34 of the switch 21, and this contact member will be moved by the weight 36 to close the switches 14 and 15 and also to break the circuit

through the opening coil 19 and complete a circuit through the indicating lamps 23. The attention of the attendant will thus be drawn to the fact that the auxiliary transformer circuit has been interrupted, and, 70 since it will be impossible to complete a circuit through the opening coil 19, the switches 14 and 15 will remain closed.

Referring now to Fig. 2, a modification is illustrated as applied to a system in which 75 the main and auxiliary transformers 1 and 2 are connected in parallel with each other, the switches 14 and 15 being arranged to open and close the circuits of the main transformer windings. The operation of the apparatus is similar to that of the apparatus shown in Fig. 1 and need not be further described.

Referring now to Fig. 3, the invention is 85 illustrated as applied to a three-wire system in which the circuit connections of the main and auxiliary transformer 1^a and 2^a are arranged to be effected by means of a single switch, in the manner set forth in my application, Serial No. 489,253, filed April 12, 90 1909, the arrangement of the means for controlling the closing and opening coils of the switches 14 and 15 and for preventing these switches from being opened when a fuse 41 in the secondary circuit of the main transformer has been destroyed, being similar to those already described with reference to Fig. 1.

Referring now to Fig. 4, a three-wire distribution system is illustrated in which main 10 and auxiliary transformers 1^a and 2^a are connected in parallel with each other, the connections of the main and auxiliary transformers on the primary side of the system being similar to those illustrated in Fig. 2. 10 The secondary winding of the main transformer is divided at its middle point into two equal portions 42^a, 43 and the adjacent ends of the portions 42^a, 43 are connected to the two fixed terminals 12 and 13 of the 1 switch 14, the neutral wire 44 of the distributing circuit being connected to the movable bridge piece 45 of the switch. The operation of the apparatus is as follows: When the switch 14 is open, the circuit of 1 the main transformer is broken and the portion 42^a and 43 of the transformer winding are also disconnected from the neutral wire 44 of the system, whereas, when the switch is closed, the two portions 42^a and 43 of the main transformer winding are connected in series and the neutral wire 44 is joined to the middle point thereof. The remainder of the connections of the system of Fig. 4 are similar to those already described and need not be more particularly referred to.

It will be understood that any one of the systems which I have shown and described may be further modified by utilizing any other known means in lieu of that specifi-

cally set forth for modifying the action of the electro-magnet 29 of the relay switch 26 or protecting its winding from injury by the heating action of excessive currents.

6. I claim as my invention:

1. In a system of alternating current electrical distribution, the combination with a main and an auxiliary transformer, of means for automatically adjusting the transformer connections in accordance with the load, an electro-magnetically operated relay switch for controlling said adjusting means, and means for reducing the current supplied to the operating magnet of the relay switch.

10 2. In a system of alternating current electrical distribution, the combination with a main and an auxiliary transformer, mechanically connected switches for adjusting the circuit connections of the primary and secondary transformer windings, an electro-magnetically operated relay switch for controlling the operation of said mechanically connected switches, and means for reducing the current supplied to the operating magnet of the relay switch.

15 3. In a system of alternating current electrical distribution, the combination of main and auxiliary transformers, of interconnected switches for adjusting the circuit connections of the primary and secondary windings of said transformers, means tending to close said interconnected switches and a fuse in the secondary circuit of one of said transformers which serves to prevent said switch-

20 closing means from operating until ruptured by an excessive current.

25 4. In a system of alternating current electrical distribution, the combination with a main and an auxiliary transformer, of mechanically connected and electro-magnetically operated switches for adjusting the primary and secondary circuits of said

transformers, a relay switch for controlling the supply of current to the operating coils of said mechanically connected switches, a 45 mechanical means tending to close said connected switches, a latch for retaining said closing means in inoperative position, and a fuse in the secondary circuit of one of said transformers for releasing said latch when 50 traversed by an excessive current.

5. In a system of alternating current electrical distribution, the combination with a main and an auxiliary transformer, of mechanically connected main switches for adjusting the primary and secondary circuit connections of said transformers, actuating coils for said main switches, an electro-magnetically operated relay switch for controlling the circuits of the actuating coils of 60 said main switches, a series transformer in the main circuit for supplying current to the actuating coil of said relay switch, and connections to one of the main switches for short-circuiting a portion of the primary 65 winding of said series transformer.

6. In a system of alternating current electrical distribution, the combination with a main and an auxiliary transformer, of means for automatically adjusting the circuit connections of said transformer in accordance 70 with the load, an electromagnetically operated relay switch for controlling said adjusting means, and means for varying the ampere turns of the operating magnet of 75 said relay switch.

In testimony whereof, I have hereunto subscribed my name this 23rd day of June, 1909.

JOHN SEDGWICK PECK.
